(57) CLAIM

The ornamental design for an item holder sleeve, as shown and described.

DESCRIPTION

FIG. 1 is a perspective front view of an item holder sleeve in an embodiment of the present invention;

FIG. 2 is a front view of the item holder sleeve of FIG. 1;

FIG. 3 is a rear view of the item holder sleeve of FIG. 1;

FIG. 4 is a top view of the item holder sleeve of FIG. 1;

FIG. 5 is a bottom view of the item holder sleeve of FIG. 1;

FIG. 6 is a left side view of the item holder sleeve of FIG. 1;

FIG. 7 is a right side view of the item holder sleeve of FIG. 1; and,

FIG. 8 is a perspective view of an item holder sleeve of FIG. 1 in a rolled configuration.

The broken lines showing are included for the purpose of illustrating portions of the article that form no part of the claimed design.
